MARKING DEVICE

Ira. S. Gottscho, Milburn, N. J., assignor to
 Adolph Gottscho, Inc., Hillside, N. J., a corpora-
 tion of New York

Application May 26, 1951, Serial No. 228,459

18 Claims. (Cl. 101—38)

1 The present invention relates to marking devices and particularly to a device for marking the interior surfaces of tubular articles.

In packaging and selling various web, strip or elongated strand materials, such as adhesive, masking, mending or friction tape, gauze bandage, and twine or string, it is common practice to wrap the web, strip or strand around a central, hollow, tubular core, and in order to identify the material or its source markings are usually applied to the exposed interior surface of the tubular core. Machines that have heretofore been available are not capable of efficiently printing the desired markings on the interior surface of such tubular cores and, therefore, the markings have been either applied to gummed label strips which are then secured in the core by a separate operation, or the markings are applied to the material from which the core is formed while such material is flat and before it is manipulated into a tubular form.

Therefore, the primary object of the present invention is to provide an efficient and simple device for applying markings to the interior surfaces of tubular cores or similar articles.

Another object is to provide a device, preferably operating on the offset printing principle, for applying printed matter to the interior surfaces of tubular cores or similar articles of relatively small internal diameter.

Another object resides in the provision of a device, preferably operating on the rotary offset printing principle, for applying printed matter to the interior surfaces of tubular cores or similar articles, wherein the rotary printing element or cylinder is repeatedly moved axially between an inking station, at which an ink impression is applied to the printing element, and a printing station, at which the element extends into the interior of a rotatably supported tubular core or similar article to transfer the ink impression to the latter so that the mechanism for applying the ink impression to the printing element is remote from the tubular core being printed and the radial dimension of the printing element is the only factor determining the minimum diameters of the tubular cores or similar articles that may be printed.

Another object resides in the provision of a device, preferably operating on the rotary offset printing principle, of the character heretofore indicated, which is constructed and arranged so that the printing element is not in contact with either the ink impression applying mechanism or the article being printed during axial move-

ments thereof, to thereby prevent smearing of the ink or blurring of the printed impression.

Still another object resides in the provision of a device, preferably operating on the rotary offset printing principle, of the character heretofore described, which includes a driving roller engageable with the article at the printing station for rotating such articles and for holding the latter at the printing station, and wherein the driving roller is so arranged and mounted as to periodically move to a release position free of the printed article during the disposition of the printing element at the inking station, so that the printed article may be easily replaced by another article to be printed.

A further object is to provide a marking device of the described character in a simple and relatively inexpensive manner and which may be easily maintained and serviced.

The above as well as other and further objects, features and advantages of the invention will be manifest from the following description and the accompanying drawings.

In accordance with the invention, the foregoing objects are accomplished by providing a marking device which comprises a frame, a rotary printing element supported on the frame and axially movable between an inking station and a printing station, an ink impression applying roller at the inking station, a support for rotatably carrying a tubular article at the printing station in position to receive the printing element in the interior thereof, the printing element having a raised portion at the circumference for engagement with a printing plate on the ink impression applying roller at the inking station and with the tubular article at the printing station so that the surface of the printing element is spaced from the ink impression applying roller and from the article at the respective stations when portions of the circumference, other than the raised portion, face toward the ink impression applying roller or the article, a driving roller at the printing station, a rockable support for the driving roller to move the latter into and out of engagement with an article at the printing station, and synchronized means for rotating the printing element, the ink impression applying roller and the driving roller, for moving the printing element axially, and for rocking the driving roller support so that the printing element is moved axially only when it is rotated to positions in which the surface is spaced from either the ink impression applying roller or the article being printed and the driving roller is rocked out

of engagement with the article during the interval when the printing element is engaged by the ink impression applying roller at the inking station.

In the drawings wherein a preferred embodiment of the invention is illustrated:

Fig. 1 is a top plan view partly broken away and in section, of a marking device embodying the present invention;

Fig. 2 is a top plan view, partly broken away and in section, of an element included in the device of Fig. 1;

Fig. 3 is a vertical sectional view taken along the line 3—3 of Fig. 1;

Fig. 4 is a front elevational view of the marking device of Fig. 1, with a portion of the frame broken away;

Fig. 5 is a vertical sectional view taken along the line 5—5 of Fig. 1;

Fig. 6 is a side elevational view of the cam member effecting axial movements of the printing element in the device of Fig. 1;

Fig. 8 is a fragmentary front elevational view of the marking device, showing the positions of the printing element and the article driving roller during printing of the article;

Fig. 9 is a fragmentary front elevational view of the marking device showing the positions of the printing element and the article driving roller during application of the ink impression to the printing element;

Fig. 10 is a sectional view taken along the line 10—10 of Fig. 1; and

Fig. 11 is a sectional view taken along the line 11—11 of Fig. 1.

Referring to the drawings in detail, and more particularly to Figs. 1-5 thereof, there is shown a marking device, which is merely illustrative of the present invention and is generally indicated by the reference numeral 19, including a frame for supporting the various elements of the device and preferably formed of a horizontal base plate 12, two parallel vertical plates 14 and 16 extending transversely along the entire width of the base plate 12 and spaced from the forward edge of the latter, and a vertical front plate 18 at the forward edge of the base plate and extending substantially halfway across the latter. Spacers 20 are secured between the vertical plates 14 and 16 at the upper corners thereof and similar spacers 22 extend between the vertical plate 16 and the front plate 18 at the upper corners of the latter so that the frame structure is suitably rigid.

All of the movements of the marking device are preferably effected by an electric motor 24 (Figs. 1 and 5), mounted upon the base plate 12 adjacent the rear thereof, and including suitable reduction gearing 26 driving a sprocket 28 (Fig. 5) which rotates about a horizontal, longitudinally extending axis. A main shaft 30 is journaled in a bearing assembly 32, carried between the vertical plates 14 and 16 substantially at the centers of the latter, and the main shaft extends forwardly of the plate 16 and to the rear of the plate 14. A sprocket 34 is fixed on the rear end of the main shaft 30, and a chain 36 is trained over the sprockets 28 and 34 for transmitting the rotation of the motor to the main shaft.

A bearing assembly 38, shown partly broken away and in section in Fig. 1, is supported below and in line with the vertical plates 14 and 16 at one side between the vertical plates 14 and 16 at one side

of the bearing assembly 32 with its axis registering substantially with the central portion of the front plate 18. A cylindrical sleeve or bushing 40 is rotatably mounted in the bearing assembly 38 and extends forwardly through the vertical plate 16. Meshing spur gears 42 and 44 (Figs. 1 and 3) are fixed to the main shaft 30 and the sleeve 40, respectively, in front of the vertical plate 16 so that the sleeve will rotate in fixed relation to the main shaft. The gears 42 and 44 are preferably dimensioned so that the sleeve 40 is rotated two revolutions during each revolution of the main shaft. A shaft 46 for supporting the printing element is slidably extended through the sleeve 40 and may be either splined or keyed in the latter so as to be rotated therewith. The shaft 46 extends out of one end of sleeve 40 to the rear of the plate 14 for engagement by a cam member, generally indicated by the numeral 48, which is fixed on the main shaft 30, and also extends out of the forward end of the sleeve to carry the printing element 50 at its forward end.

The printing element or roller 50 includes a hub 52 threadedly carrying a set screw for fixing the printing element relative to shaft 46, and a cylindrical forward portion having a raised segment 54 of increased radius extending over approximately one half of the surface (Fig. 4) to receive the off-set ink impression. A circular opening 56 (Fig. 4) is formed in the front plate 18 concentric to the axis of rotation of the shaft 46 and is dimensioned to loosely receive the printing element 50 when the latter is moved forwardly by the action of the cam member 48 hereinafter described in detail.

A printing station is defined at the forward face of the front plate 18, and at such station a circular bearing ring 58 is secured to the front plate substantially tangential to the raised portion 54 of the printing element. A pair of rollers 60 extend forwardly from the front plate at opposite sides of the opening 56 and are positioned to engage the inner surface of a tubular article 62, such as a core for a roll of tape, gauze or string, as shown in broken lines in Figs. 8 and 9, and rotatably support such article so that the raised portion 54 of the printing element, when extended forwardly through the opening 56, is engageable with the inner surface of the supported article (Fig. 8).

As seen in Fig. 10, each of the rollers 60 is rotatably mounted on an eccentric portion of an adjustable support bolt 64 mounted rotatably on the front plate 18. The adjustable eccentric bolts 64 provide for either raising or lowering the related rollers 60 at the opposite sides of the opening 56 so that the contact of the printing element 50 with a tubular article supported on the rollers 60 may be conveniently varied.

In order to drive or rotate the article 62 at the printing station, and to resist the upward pressure of the printing element during the printing phase of the operation of the marking device, an assembly as shown in Figs. 2 and 3 of the drawing is provided. This assembly includes a bell-crank having angularly related arms 64 and 66 and formed with hollow bosses 68 and 70 at the junction of the arms and midway along the arm 64, respectively, as well as a tubular extension 72 at the free end of the arm 64. A stub shaft 74 (Fig. 2) extends at one end in to the boss 68 and is mounted at its other end in a bushing 76 carried by the vertical plate 16 substantially below and in line with the main shaft 30. A spur gear 78 is rotatable on the stub shaft 74 between

the boss 63 and the forward face of plate 16 and meshes with the gear 42 on the main shaft 38. An idler spur gear 80 is rotatably mounted on the boss 78 and meshes with the gear 78 as well as with a gear 82 fixed on the rear end of a shaft 84 which is journaled in the tubular extension 72 at the end of the arm 64. A driving roller 86 is fixed to the forward end of the shaft 84 and the front plate 18 is formed with a vertically elongated opening 88 (Fig. 4) through which the forward portion of tubular extension 72 projects to position the driving roller in front of the plate 18 for engagement with the inner surface of a tubular article (Fig. 8).

The shaft 38 and gear 42 in the illustrated embodiment, as viewed from the front of the device (Figs. 3, 4 and 5), are rotated in a clockwise direction and, therefore, the printing element 58 and the driving roller are both rotated in a counterclockwise direction, and the several gears heretofore described are dimensioned so that the peripheral speed of the printing element at the raised portion 54 of the surface thereof is the same as the peripheral speed of the driving roller 86. Thus, the driving roller when in operative position (Fig. 8) drives a tubular article 62 at a speed at the inner surface thereof equal to the peripheral speed of the raised portion of the printing element which is engageable with such inner surface so that there will be no blurring of the printed impression by reason of relative movement between the printing element and the surface of the article being marked.

The bell crank is continuously and resiliently urged in a counter-clockwise direction, as viewed in Fig. 3, by a tension spring 90 secured at one end to the arm 64 and at its other end to a pin or other suitable fixed support 92 which may be mounted on the rear face of the front plate 18 below the arm 64. Thus, the driving roller 86 is resiliently urged downwardly into contact with the inner surface of the tubular article or core to hold the article on the supporting rollers 60 and to resist the pressure of the printing element which acts on the article in an opposite direction. In order to provide periodic rocking of the bell crank for movement of the driving roller 86 away from the inner surface of an article at the printing station so that the article may be easily and conveniently replaced after it has been marked, a radial cam 94 (Figs. 1, 3 and 9) is fixed on the main shaft 38 and the periphery of such cam is engaged by a cam follower, in the form of a roller 96, carried by the free end of the arm 66. The cam 94 is formed with a radially extended portion, which, when engaged by the roller 96, rocks the bell crank in a clockwise direction to raise the driving roller and release the tubular article or core. The angular position of the cam 94 on the main shaft 38 and the angular extent of the radially extended portion thereof are related to the configuration of the cam 48 so that the driving roller 86 is moved to its inoperative or released position (Fig. 9) when the printing element moves axially to the rear to its inking position and so that the driving roller is returned to its operative and driving position (Fig. 8) when the printing element returns to the printing station and the raised portion 54 thereof engages the article being marked. The eccentric nature of the mounting of the rollers 60 further provides for the adjustment of the contact pressure between the driving roller 86 and the tubular article 62 during the printing phase of the operating cycle.

A coil spring 98 (Fig. 1) is disposed around the rear portion of shaft 46 and abuts at one end against a cover plate of the bearing assembly at the rear face of the plate 14 and at its other end against a shoulder or abutment 102 at the rear end of the shaft 46. Thus, the spring 98 is under compression and resiliently urges the shaft 46, and hence the printing element, rearwardly and away from the printing station.

The cam member 48 for controlling the axial movements of the shaft 46 and hence of the printing element 58, includes a central hub 102 (Figs. 5 and 6) carrying suitable set screws for securing the cam member to the main shaft 38 and a circular plate 104 extending from the hub and having a diameter so that the shaft 46 bears against the front face thereof adjacent its periphery. The cam member 48 is positioned on the main shaft 38 so that the printing element 58 is disposed at an inking station, hereinafter more specifically defined, when the rear end of the shaft 46 abuts against the front face of the circular plate 104 under the influence of the spring 98, as in Figs. 1 and 5. In order to move the shaft 46 forwardly to position the printing element at the printing station, a flange 106 extends axially from the front face of the circular plate 104 along a portion of the edge of the latter. The depth of the flange 106 corresponds to the distance the printing element 58 moves axially between the inking and printing stations. Thus, when the cam member 48 is rotated from the position of Figs. 1 and 5 to register the flange 106 with the shaft 46, the latter is displaced forwardly to extend the printing element through the opening 58 of the plate 18. The opposite ends of the flange 106 are provided with inclined portions 108 and 110 merging into the front face of the circular plate 104 and correspond to the movements of the printing element from the inking station to the printing station and from the printing station to the inking station, respectively. The angular positions of the inclined end portions 108 and 110 are related to the rotation of the shaft 46 so that either of these inclined end portions registers with the rear end of the shaft 46 only when the raised portion 54 of the printing element is facing away from the article being marked at the printing station and away from the roller applying the ink impression at the inking station.

For the purpose of applying the ink impression to the printing element at the inking station, an ink impression applying roller 112 is fixed to the main shaft 38 for rotation with the latter and is formed with a diameter so that a printing plate on the periphery of the roller is engageable with the raised portion 54 of the printing element. The radii of the roller 112 and the raised portion 54 are proportional to the ratio of the gear 42 to the gear 44 so that the engageable surfaces of the printing plate on the roller and of the printing element move at the same peripheral speed to thereby effect the transfer of an ink impression to the printing element without smearing of the ink. The ink supply is carried in an open reservoir 114 which is removably mounted on the front of the vertical plate 18 to the side of plate 18. An ink supplying roller 116 is fixed on the shaft 118 journaled in suitable anti-friction bearings mounted in the eccentric bore of a bearing sleeve 120 carried for rotatable adjustment by the plates 14 and 16 (Fig. 11) and dips into the reservoir 114. An ink transfer roller 122, in peripheral engagement with both the ink supplying roller 116

and the ink impression applying roller 112, is fixed on a shaft 124 journalled in a manner similar to that illustrated for shaft 118, within an adjustable, eccentric bearing sleeve 126 mounted between the plates 14 and 16. A spur gear 128 is fixed on the shaft 124 and meshes with the gear 42 on the main shaft, and a spur gear 130 is fixed to the shaft 118 and meshes with the gear 128 so that the transfer roller 122 and the supplying roller 116 are positively rotated in timed relation to the rotation of the main shaft 38 and hence to the rotation of the ink applying roller. The gears 128 and 130 are so dimensioned that the surface speeds thereof are the same as the surface speed of the roller 112. While I have shown a driving arrangement for the ink supplying roller 116 which includes the gears 128 and 130, it is to be understood that the gear 130 may be omitted and the rotation of the roller 116 effected merely by its frictional engagement with the roller 122.

The adjustable eccentric bearing sleeves 126 and 128 provide for varying the contact pressure between the rollers 116 and 122, and the sleeve 126, when angularly adjusted, is effective to vary the contact pressure between the ink transfer roller 122 and the ink impression applying roller 112. Thus, the contact pressures may be controlled so that roller 116 presses against roller 122 to doctor the ink on the latter, and so that the roller 122 has mere "kiss," or light, contact with the printing plate carried by the roller 112.

Although the preferred arrangement heretofore described is of the type known as an off-set printed, that is, one in which the ink impression is applied to the surface of a roller which then transfers the ink impression to the article being marked, it is to be understood that the invention contemplates other printing arrangements, specifically an arrangement in which the printing element 58 carries a printing plate on its raised peripheral portion 54 and the roller 112 only functions as an ink applying roller to transfer ink to the surface of the printing plate when the element 58 is disposed at the printing station.

While the operating cycle of the marking device embodying the present invention may be changed to vary the duration of the periods for which the printing element is disposed at the printing station and at the inking station, so long as axial movement of the printing element occurs only when the raised portion 54 thereof is facing away from the article being marked or the roller 112, as the case may be, in the illustrated embodiment the various phases of operation correspond to the angular displacement of the cam 48 as follows:

The portion of the cam corresponding to the positioning of the printing element at the inking station extends over an angle of approximately 140 degrees;

The portion of the cam corresponding to the movement of the printing element from the inking station to the printing station, that is the inclined portion 108 of the flange, extends over an angle of approximately 85 degrees;

The portion of the cam corresponding to the positioning of the printing element at the printing station, that is the straight portion of the flange 108, extends over an angle of approximately 95 degrees; and

The portion of the cam corresponding to the movement of the printing element back to the inking station, that is the inclined portion 110,

75 article and inking means, respectively.

extends over an angle of approximately 40 degrees.

Since the shaft 46 rotates at twice the speed of the shaft 38, the printing element 58 will be angularly displaced approximately 280 degrees while at the inking station, approximately 170 degrees during movement toward the printing station, approximately 190 degrees while at the printing station and approximately 80 degrees during its movement back to the inking station, and, as previously indicated, the printing element is positioned on the shaft 46 so that its movement toward the inking station is completed before the leading edge of the raised portion 54 thereof comes in contact with the ink impression applying roller 112 and its movement toward the printing station does not commence until the trailing edge of such raised portion clears the roller 112. With the angular displacements of the various portions of the cam 48 set forth above, the establishment of the stated relationship between the raised portion 54 and the roller 112 insures that movement of the printing element toward the printing station will be completed before the leading edge of such raised portion comes in contact with the article being marked and that axial movement of the printing element in the direction returning the latter to its inking station does not commence until the trailing edge of the raised portion is clear of the article being marked.

From the above it is apparent that the present invention provides a marking device, preferably of the rotary off-set printing type, for marking the inner surfaces of tubular members, such as cores for various tapes, gauze, string or twine, wherein the ink impression applying roller is positioned at an inking station remote from the printing station and the printing element is periodically moved axially between the inking station and the printing station in a manner to prevent smearing of the ink on the printing element as well as blurring of the printed impression; and further wherein the device includes a driving or feeding roller engageable with the tubular article at the printing station during the printing phase of the operational cycle of the device to rotate the article being printed at the same speed at its inner surface as the surface speed of the printing element and moving away from the article when the printing element is retracted to the inking station to permit easy replacement of the article.

Having described an illustrative embodiment of the invention, it is to be understood that I do not wish to be limited to the precise structure thereof as obviously numerous changes and modifications may be effected therein without departing from the spirit or scope of the invention.

What I claim is:

1. A printing device for marking the inner surfaces of tubular articles comprising means for rotatably supporting a tubular article at a printing station; a rotating printing element of segmental configuration movable axially between said printing station, at which it is peripherally engageable with the inner surface of a tubular article there supported, and an inking station remote from said printing station; inking means peripherally engageable with said printing element at said inking station to apply ink to said element; and means reciprocating said segmental printing element axially between said printing and inking stations when said printing element is angularly positioned away from the tubular

2. A rotary printing device for marking the inner surfaces of tubular articles comprising means for rotatably supporting a tubular article at a printing station; a rotating printing element of segmental configuration movable axially between said printing station, at which it extends into a tubular article there supported for peripheral engagement with the inner surface of the latter, and an inking station remote from said printing station; inking means peripherally engageable with said printing element at said inking station for applying ink to said element; means reciprocating said segmental printing element axially between said printing and inking stations when said printing element is angularly positioned away from the tubular article and printing means, respectively; and a driving roller engageable with a tubular article at said printing station for rotating the article so that the speed at the inner surface of the latter is the same as the peripheral speed of the rotating printing element.

3. A rotary printing device for marking the inner surfaces of tubular articles comprising means for rotatably supporting a tubular article at a printing station; a rotating printing element of segmental configuration movable axially between said printing station, at which it extends into a tubular article there supported for peripheral engagement with the inner surface of the latter, and an inking station remote from said printing station; inking means peripherally engageable with said printing element at said inking station for applying ink to said element; means reciprocating said segmental printing element axially between said printing and inking stations when said printing element is angularly positioned away from the tubular article and printing means, respectively; and a driving roller engageable with the inner surface of a tubular article at said printing station and positioned to contact such inner surface along a line substantially diametrically opposed to the contact line of said printing element with the article for opposing the contact pressure of said printing element and for rotating the article so that the speed at the inner surface of the latter is the same as the peripheral speed of the rotating printing element.

4. A rotary printing device for marking the inner surfaces of tubular articles comprising means for rotatably supporting a tubular article at a printing station; a rotating printing element of segmental configuration movable axially between said printing station, at which it extends into a tubular article there supported for peripheral engagement with the inner surface of the latter, and an inking station remote from said printing station; inking means peripherally engageable with said printing element at said inking station for applying ink to said element; means reciprocating said segmental printing element axially between said printing and inking stations when said printing element is angularly positioned away from the tubular article and printing means, respectively; a driving roller engageable with the inner surface of a tubular article at said printing station along a contact line substantially diametrically opposed to the contact line between said printing element and the article; and mounting means for said driving roller displaced in coordination with said means reciprocating said printing element to move said driving roller away from the inner surface of the article when said element is moved

10 to said inking station thereby permitting replacement of the article.

5. A rotary printing device for marking the inner surfaces of tubular articles comprising means for rotatably supporting a tubular article at a printing station; a rotating printing element formed with a radially raised portion and movable axially between said printing station, at which it extends into a tubular article there supported for peripheral engagement of said raised portion with the inner surface of the article, and an inking station remote from said printing station; inking means peripherally engageable with said raised portion of said element at said inking station for applying ink to such raised portion; and means reciprocating said printing element axially between said inking and printing stations and being coordinated with the rotation of said printing element so that axial movement of the latter is effected only when said raised portion is angularly disposed to be disengaged from said inking means as well as from the inner surface of the article.

6. A rotary printing device for marking the inner surfaces of tubular articles comprising means for rotatably supporting a tubular article at a printing station; a rotating printing element formed with a radially raised portion and movable axially between said printing station, at which it extends into a tubular article there supported for peripheral engagement of said raised portion with the inner surface of the article, and an inking station remote from said printing station, inking means peripherally engageable with said raised portion of the printing element at said inking station for applying ink to said raised portion; means coordinated with the rotation of said printing element and reciprocating the latter axially between said inking and printing stations so that axial movement of said element is effected only when said raised portion is angularly disposed to be disengaged from said inking means as well as from the article; and a driving roller engageable with a tubular article at said printing station for rotating the article so that the speed at the inner surface thereof is the same as the peripheral speed of the raised portion of the rotating printing element.

7. A rotary printing device for marking the inner surfaces of tubular articles comprising means for rotatably supporting a tubular article at a printing station; a rotating printing element formed with a radially raised portion and movable axially between said printing station, at which it extends into a tubular article there supported for peripheral engagement of said raised portion with the inner surface of the article, and an inking station remote from said printing station; inking means peripherally engageable with said raised portion of the printing element at said inking station for applying ink to said raised portion; means coordinated with the rotation of said printing element and axially reciprocating the latter between said inking and printing stations so that axial movement of said element is effected only when said raised portion thereof is angularly disposed to be disengaged from said inking means as well as from the article; and a driving roller engageable with the inner surface of a tubular article at said printing station along a contact line diametrically opposed to the line of contact of said raised portion with the inner surface of the article for opposing the contact pressure of the printing ele-

11

ment against the article and for rotating the latter so that the speed at the inner surface of the article is the same as the peripheral speed of the raised portion of said printing element.

8. A rotary printing device according to claim 7, including a rockable support for said driving roller, and actuating means for said support coordinated with said means axially reciprocating said printing element to rock said support to a position spacing said driving roller from the inner surface of a tubular article at said printing station when said printing element is moved axially to said inking station so that the tubular article may be easily replaced.

9. A rotary printing device for marking the inner surfaces of tubular articles comprising a frame, a shaft journaled in said frame and carrying a printing element of segmental configuration at one end thereof, said shaft being axially movable relative to said frame to effect axial movements of said element between a printing station and an inking station, inking means at said inking station for peripheral engagement with said printing element, means on said frame for rotatably supporting a tubular article at said printing station in position to be engaged at its inner surface by the periphery of said printing element, means rotating said shaft, cam means coordinated with said rotating means and acting against the other end of said shaft to intermittently effect axial movement of the latter in one direction when said segmental printing element is angularly positioned away from the tubular article and said inking means, and spring means engaging said shaft continuously urging the latter axially in the opposite direction.

10. A rotary printing device for marking the inner surfaces of tubular articles comprising a frame, a main shaft journaled in said frame, means rotating said main shaft, an axially movable shaft journaled in said frame and carrying a segmental printing element on one end to move axially between a printing station and an inking station, means transmitting the rotation of said main shaft to said axially movable shaft, inking means peripherally engageable with said printing element at said inking station for applying ink to the periphery of said element, means on said frame for rotatably supporting a tubular article at said printing station in position to be engaged at its inner surface by the periphery of said printing element, spring means continuously urging said axially movable shaft in the direction of said inking station, and cam means carried by said main shaft and engaging said axially movable shaft to intermittently move the latter in opposition to said spring means for displacing said printing element to said printing station when said printing element is angularly positioned away from the tubular article and said inking means.

11. A rotary printing device according to claim 10, including a driving roller at said printing station engageable with the inner surface of a tubular article supported thereat, and means driven by said main shaft rotating said driving roller so that the linear speed at the inner surface of an article engaged by the latter is the same as the peripheral speed of said printing element.

12. A rotary printing device according to claim 10, including a driving roller engageable with the inner surface of a tubular article supported at said printing station along a contact line substantially diametrically opposed to the line of contact of said raised segment with the inner surface, spring means constantly urging said member to rock in the direction engaging said driving roller against the inner surface of the article so that said driving roller resists the contact pressure of said raised segment against the article, means driven by said main shaft rotating said driving roller at a

12

contact of said printing element with such inner surface, a rockable arm pivoted on said frame and carrying said driving roller, spring means acting on said arm to continuously urge said roller against the inner surface of an article at said printing station so that said roller opposes the contact pressure of said printing element, gear means driven by said main shaft and rotating said driving roller so that the inner surface of the tubular article is moved at the same speed as that at the periphery of said printing element, and cam means on said main shaft intermittently rocking said arm to move said roller away from the tubular article when said printing element is displaced axially to said inking station so that the tubular article may be easily replaced.

13. A rotary printing device for marking the inner surfaces of tubular articles comprising a frame, a main shaft journaled in said frame, means rotating said main shaft, an axially movable shaft journaled in said frame and carrying a printing element on one end to move axially between a printing station and an inking station, said printing element including a radially raised segment, means driven by said main shaft and rotating said axially movable shaft, an ink applying roller rotatable with said main shaft to one side of said axially movable shaft at said inking station and peripherally engageable with said raised segment when said printing element is disposed at said inking station, means on said frame for rotatably supporting a tubular article at said printing station in position to be peripherally engaged at its inner surface by said raised segment of the printing element, spring means acting on said axially movable shaft for continuously urging the latter to a position disposing said printing element at said inking station, and a cam member fixed on said main shaft and engageable with said axially movable shaft, said cam member being formed to reciprocate said main shaft for moving said printing element between said inking and printing stations and so that such axial movement occurs only when said raised segment of the printing element is angularly positioned to be disengaged from both said ink applying roller and the tubular article.

14. A rotary printing device according to claim 13, including a driving roller supported at said printing station and rotatable about an axis parallel to the axis of rotation of said printing element, said driving roller being engageable with the inner surface of a tubular article at said printing station, and means driven by said main shaft rotating said driving roller so that the tubular article is rotated at a linear speed at its inner surface the same as the peripheral speed of said raised segment of the printing element.

15. A rotary printing device according to claim 13, including a driving roller, a rockable member pivoted on said frame and rotatably supporting said driving roller at said printing station in position to engage the inner surface of a tubular article supported at the printing station along a contact line substantially diametrically opposed to the line of contact of said raised segment with the inner surface, spring means constantly urging said member to rock in the direction engaging said driving roller against the inner surface of the article so that said driving roller resists the contact pressure of said raised segment against the article, means driven by said main shaft rotating said driving roller at a

13

peripheral speed the same as the peripheral speed of said raised segment, and a cam member on said main shaft actuating said member and rocking the latter when said printing element is disposed at said inking station to disengage said driving roller from the inner surface of the article so that the latter may then be easily replaced.

16. A rotary printing device according to claim 13, including an ink reservoir mounted on said frame, an ink supplying roller journalled in said frame and dipping into said reservoir, an ink transfer roller journalled in said frame and peripherally contacting said ink applying roller and said ink supplying roller at spaced lines of contact, and means driven by said main shaft rotating said ink supplying and transfer rollers at peripheral speeds the same as the peripheral speed of said ink applying roller.

17. A rotary printing device for marking the inner surfaces of tubular articles comprising a support plate having an opening formed therein; a pair of support rollers extending axially from said plate at the opposite sides of said opening for engaging the interior surface of a tubular article to thereby support the tubular article at a printing station; a rotating printing element having a radially raised segment and movable axially through said opening between said printing station, at which it extends into a tubular article there supported for peripheral engagement of said raised segment with the inner surface of the latter, and an inking station remote from said printing station; inking means peripherally engageable with said raised segment of the printing element at said inking station for ap- 35

14

plying ink to said element; means reciprocating said printing element axially between said printing and inking stations when said raised segment is angularly disposed away from the tubular article and said inking means, and a driving roller engageable with the inner surface of a tubular article at said printing station and positioned to contact such inner surface along a line substantially diametrically opposed to the line of contact of said printing element with the article for opposing the contact pressure of said printing element and for rotating the article so that the speed at the inner surface of the latter is the same as the peripheral speed of the rotating printing element.

18. A rotary printing device for marking the inner surfaces of tubular articles as set forth in claim 17, including means mounting said support rollers on said support plate and adjustable to vary the positions of the axes of said support rollers relative to the axes of said printing element and driving roller to thereby provide for the adjustment of the contact pressures of said printing element and driving roller with a tubular article at said printing station.
